UNITED STATES PATENT OFFICE.

ANNIE M. WILSON, OF ALDAN, PENNSYLVANIA.

DESIGN FOR A POISON-MARKER.

50,371.

Specification for Design.

Patented Feb. 20, 1917.

Application filed February 7, 1916. Serial No. 76,870. Term of patent 7 years.

To all whom it may concern:

Be it known that I, ANNIE M. WILSON, a citizen of the United States, residing at Aldan, in the county of Delaware and State of Pennsylvania, have invented a new, original, and ornamental Design for Poison-Markers, of which the following is a specification, reference being had to the accompanying drawing, forming a part thereof.

The figure is a plan view of a poison marker, showing my new design.

I claim:

The ornamental design for a poison marker, as shown.

ANNIE M. WILSON.
